UNITED STATES PATENT OFFICE

2,685,845

RAILWAY CAR RADIUS ROD

Alfred A. Gassner, New York, and George B. Parsons, Roosevelt, N. Y., assignors to ACF Industries, Incorporated, a corporation of New Jersey

Application February 18, 1947, Serial No. 729,236

9 Claims. (Cl. 105—4)

1

This invention relates to railroad rolling stock and more particularly to mechanism connecting the axle and the framing of a car.

In one type of railroad train each car is supported at the rear end upon two track wheels and connected at the front end with the preceding car by means of a draft coupling. In addition to the draft coupling, the adjacent upper end portions of adjacent cars are sometimes provided with weight sustaining means consisting of side connections arranged to permit limited relative movement of the cars.

With this trailer type of car the two track wheels are journalled on a transversely extending axle structure and the connections between the axle structure and framing must include connection means that will permit limited freedom of movement of the axle and framing relative to each other.

An object of this invention is to provide a car, of the type referred to, with improved means controlling relative movement of the axle and the framing in both longitudinal and vertical directions.

Another object of the invention is to provide a car, of the type referred to, with improved connecting mechanism for resisting upward movement of the axle when the wheels are braked.

A further object of the invention is to provide a car, of the type referred to, with mechanism whereby torsional shear of rubber insulates the car body and track rails from torque reactions through the axle.

Still another object of the invention is to provide a car, of the character referred to, with improved mechanism between the axle and framing for restricting relative vertical, longitudinal and transverse movement of the framing and the axle.

These and other objects of the invention will be apparent to those skilled in the art from a study of the following description and accompanying drawings, in which:

Figure 1 is a side elevation of several cars of a railway train of the type referred to.

Figure 2 is a plan view of the rear end of a car incorporating the invention.

Figure 3 is an elevational view of the rear end of a car.

Figure 4 is a side elevation of a rear end of a car.

Figure 5 is a side elevation of the front end of a car.

Figure 6 is a view of a torque reaction and radius rod device taken on line 6—6 of Figure 2.

Figure 7 is a sectional view taken on line 7—7 of Figure 6.

Figure 8 is a fragmentary view of one end of the torque reaction and radius rod device.

Figure 9 is another fragmentary view of an edge portion of the device in Figure 6.

2

Figure 10 is a sectional view through a wheel and its axle.

Figure 11 is a view looking at the bottom of one of the anti-sway devices.

Figure 12 is a view looking at the bottom of another anti-sway device.

Figure 13 is a longitudinal sectional view of the spring rod structure of the devices shown in Figure 11.

16 The invention is shown associated with rail- way cars 10, of the trailer type, having a rear- wardly located axle structure 11 on which track wheels 12 are rotatably mounted. Auxiliary sup- porting means for the front end of the cars con-

15 sists of two jack wheel devices located one adja- cent each side of the car. Each auxiliary sup- porting device comprises a leg 13 carrying a track wheel 14 and fixed to shaft 15 mounted to rotate in housing 16 attached to the car framing 17.

20 Suitable gearing in the housing is manually oper- able by crank 18 for lowering or raising the leg to engage or disengage the wheel with the track rail 19. The auxiliary supporting devices are en- gaged with the track rails only when cars are

25 being coupled or uncoupled or while a car is un- coupled. The two extreme positions of adjust- ment of the legs are shown in Figure 5, but to simplify the illustration the car is not elevated and the track wheel is not shown resting on the track rail when the leg is in the down position.

30 The front end of each car is attached to the rear end of the adjacent forward car by a draft coupling the details of which are shown in co- pending application Serial Number 734,465 filed

35 March 13, 1947, which has matured into Patent No. 2,630,230. The female section 20 of the cou- pling is attached to the front end of the car fram- ing 17 and the male section 21 of the coupling is attached to the central rearmost end of the car fram- ing. This male coupling section has a de- pending extension 23 utilized for purposes appear- ing hereafter.

35 In addition to the central draft coupling con- nection between adjacent cars, the forward end of each car body is supported on the preceding car body by two similar weight sustaining devices each consisting of a section 25 on one car rear end and another section 24 on the front end of the adjacent following car. Section 25 includes vertically spaced cylindrical housings 26, suitably

50 secured to the car rear end wall 27, for carrying the vertical leg 28 of a member having a hori- zontally extending coupling arm 29. Between the ends of the vertical leg and the housings are ar- ranged rubber sleeve units 30 bonded thereto. Section 24 consists of vertically spaced housings

55 31, suitably secured to the front end framing 32 of the car, carrying the ends of member 33, such ends and housings having rubber sleeves 34 therebetween and bonded thereto. Member 33

60

between the housings is formed with an opening 35 in which is fixed a rubber sleeve 36 through which coupling arm 29 of the adjacent car extends. These coupling arms may project into the end portion of the adjacent car where they are locked by removable fasteners, as indicated by numeral 37. These weight supporting devices will permit restricted relative movement of adjacent car bodies in any direction while serving as supporting and coupling means.

The axle structure 11 is of the underslung type made up of sections rigidly connected together, copending application Serial No. 733,097 filed March 7, 1947, which has matured into Patent No. 2,641,499, being directed to the details of this structure. Generally, the axle structure comprises a lower transverse member 40, upper stub axles 41 and connecting arm members 42. The lower ends of the arm members are bifurcated and clamped on the ends of the lower member by bolts 43 while the stub axles extend through upper bearing portions of the arm members and are secured thereto by bolts 44. The wheels 12 are journalled on the stub axles and the stub axles extend outside of the wheels sufficiently to provide bearing portions 45.

The car framing is supported on the axle structure by two similar strut devices 46. Each strut device comprises two telescopically associated cylinder members 47 and 48 having flanges 49 against which the ends of coil springs 50 bear, such springs encircling the leg members. The lower ends of members 48 terminate in forks 51 that are journalled on shafts 52 fixed in carriers 53 journalled on the bearing portions 45 of the stub axles and nuts 54 on the ends of the stub shafts retain the fork carriers in position axially on the stub shafts. These strut devices form the subject matter of copending application Serial No. 733,098 filed March 7, 1947, now abandoned. Members 47 terminate at their upper ends in yokes 55 that journal on pins 56 carried by brackets 60 fixed to a portion of rear bulkheads 27 on the framing.

The upper ends of the strut devices are free to pivot in a direction transversely of the car on longitudinally extending axes and the lower ends of the strut devices are free to pivot on axes extending transversely and longitudinally of the car. The strut devices angle outwardly toward the adjacent sides of the car and the springs 50 act between flanges 49 to extend the sections 47 and 48 in an axial direction to thereby suspend the car framing above the axle structure.

The axle structure is also connected with the framing by two similar devices 61 that serve as torque reaction means and radius rods. Such devices each include two rod members 62 and 63 pivoted together by pin 64 to allow relative movement thereof in a lateral direction. Rod 62 is connected to the car framing by joint device 65 having a housing 66 secured to an underframing cross member 67. The joint device 65 is of the ball type and includes spaced spherical members 68, 69 carried by housing 66 and an intermediate mating spherical flange member 70 screwed on the end of rod member 62 and secured in adjusted relation by set screw 71. Cover 72 is secured over the open end of the housing and to the adjacent rod member.

Rod member 62 is associated with the axle structure through connecting means opposing torque reaction from the axle structure. The portion 73 of the stub axles adjacent the inner side of wheels 12 is formed square for the recep-

tion of arm means in the form of disk plates 74 having square central openings 75 therethrough. Rod members 63 terminate in ring portions 76 that are arranged between plates 74, and between the ring portions of the arms and the adjacent plates is arranged rubber ring devices. Each of such rubber ring devices includes a ring of rubber 77 intermediate and bonded to metal rings 58, 59. Bolts 78 secure ears 58' on rings 10 58 to ears 78' on the rod plate members 77 and bolts 59' secure ears 57' on the rings 59 to ears 74' on the ring member 76. Bolts 78 are preferably drawn up sufficiently to place the rubber rings 77 in compression. The plates 74 are formed 15 with aligned ears 79 and a stop member 80, in the form of a spacer, is secured therebetween by bolts 81. The ring portions 76 of the rod members 63 are formed with tongues 82 disposed in spaced relation on each side of the stop member and coact with the stop member to limit the relative rotational movement between the rod members 63 and the plates 74.

It will be noted that the rubber connections 20 between the axle and the rod members will take torque reactions in shear, will resist torque reactions tending to lift the axle when the brakes are applied and twisting forces when the wheels or framing tilt. Further, the rod members and 25 their connection with the frame will lessen longitudinal shock forces transmitted to the framing and will locate the axle with the framing while allowing relative lateral movement thereof.

Means is provided for restricting and damping 30 relative movement between the axle structure and the framing in a direction transversely of the car. Such means comprises generally a spring device 80 between one side of the framing and draft coupling extension 23 and a hydraulic device 81 between the other side of the framing and such draft coupling extension. The details 35 of such means for restricting relative movement between the axle structure and the framing in a direction transversely of the car is covered in copending application Serial Number 733,096 filed March 7, 1947.

Device 80 comprises a cylinder 82 having a cap 83 on one end from which a rod 84 extends and the end of this rod is pivotally mounted on pin 85 fixed to a carrier 86 secured to the front face of one of the intermediate axle sections 42 by bolts 87. A rod 87 having a flange 95 fixed thereto extends through the other end of cylinder 82 and has an adjustable extension 96 pivotally mounted on bolt 88 carried by the draft coupling extension 23. Opposed springs 89, 90 in the cylinder act oppositely against flange 95 to normally maintain it in a position centering the framing relative to the axle structure. Device 81 includes a hydraulic two-way shock absorber having a housing 91 secured to the front face of one of the intermediate axle structure sections by bolts 98 and a movable vane section 92 carrying an arm 99 on which an extension 100 of rod 93 is pivoted. An extension 101 60 on the other end of rod 93 is pivotally mounted on pin 94 carried by draft coupling extension 23. The spring device restricts normal relative movement of the framing and axle structure in a direction transversely of the car and the hydraulic device opposes forces beyond those controlled by the spring device tending to move the framing and axle structure relatively in a direction transversely of the car.

The wheels 12 are formed of sections having 70 rubber connections and copending application

Serial Number 733,113, filed March 7, 1947, which has matured into Patent No. 2,569,617, is directed to such structure. The wheel rim 103, see Figure 10, has an inwardly extending flange 104 and hub 105 has disks 106 fixed thereto. The disk and rim flange are connected by rubber devices each consisting of metal rings 107, 108 between which is arranged a rubber ring 109. The rubber is bonded to the metal rings and the rings 107 are fixed to the hub disks 106 by bolts 110 while rings 108 are fixed to the rim flange 104 by suitable means not shown. These rubber devices will take torque reactions from the axle structure in shear and will also take vertical and longitudinal shock loads.

Brake drum 111 is fixed to the wheel disk by bolts 112 and within the drum are brake shoes 113 adapted to be actuated by suitable fluid means (not shown).

What is claimed is:

1. In a railway car having framing and a non-rotating axle carrying wheels, a rod comprised of two sections, means pivotally connecting said rod sections to permit relative movement thereof in a direction transversely of the car, a ball joint device connecting one of the rod sections to the framing, and means connecting the other rod section to the axle for limited relative rotational movement, said connecting means including rubber in shear.

2. In a railway car framing, a non-rotating axle carrying wheels, means suspending the framing on the axle, and a pair of similar connection devices each comprising arm means fixed to the axle, a two-section jointed rod, a ball joint device connecting one section of the rod to the framing in advance of the axle, and means resiliently connecting the other section of the rod to the arm means.

3. In a railway car, an axle having wheels rotatably mounted thereon, framing, a pair of similar longitudinally extending devices each comprising two sections pivotally connected to allow relative movement thereof in a direction transversely of the car, a ball joint device connecting the forward rod section to the framing, arm means fixed to the axle, and means connecting said arm means and the rear section of the rod including rubber in compression, said connection allowing limited rotation of said axle relative to said rod.

4. In a railway car, an axle carrying wheels, framing, means suspending the framing on the axle, a pair of similar longitudinally extending rods each comprising forward and rear jointed sections, a ball joint device connecting the forward rod section to the framing, means fixed to the axle, rubber means connecting the rear rod section to said means fixed to the axle, said rubber means damping torque reaction forces from the axle to the framing, and means limiting the rotational movement of the rear rod section relative to said means fixed to the axle.

5. In a railway car having framing and an axle, a combined radius rod and torque reaction device comprising arm means fixed to the axle, a rod extending longitudinally of the car and including two sections pivoted together at their adjacent ends to permit relative movement thereof in a direction transversely of the car, a universal joint means connecting one of the

rod sections with the framing, and means connecting the other rod section with the arm means to permit limited relative rotation thereof, said means connecting the rod section with the arm means including resilient torque resisting means.

6. In a railway car having framing and an axle spaced longitudinally from the framing, a radius and torque reaction device comprising arm means fixed to the axle and extending toward the framing, a sectional rod between the arm means and the framing formed of two members pivotally connected at the adjacent ends to permit relative movement of said members in a direction transversely of the car, a universal joint connecting one of said rod members to the framing, and means connecting the other rod member with said arm means in relation to permit restrained relative movement thereof in response to torque created forces.

7. In a railway car having framing and an axle spaced longitudinally from the framing, a radius and torque reaction device comprising a pair of spaced arms fixed on the axle and extending longitudinally toward the framing, a rod comprised of sections pivoted together to permit relative movement of the sections in a direction transversely of the car, a universal joint connecting one end of said rod to the framing, the other end of said rod extending between said arms, and a connection between the arms and the end of the rod extending therebetween including resilient means.

8. In a railway car having framing and an axle spaced longitudinally from the framing, a radius and torque device comprising a pair of spaced arms fixed to the axle and extending longitudinally toward the framing, a rod comprising sections pivoted together to permit relative movement of the sections in a direction transversely of the car, a universal joint connecting one end of the rod to the framing, the other end of the rod extending between the arms, rubber devices between the arms and the adjacent end of the rod, and means securing the arms with the adjacent end of the rod and with the rubber devices in compression.

9. In a railway car, a rigid non-rotating axle carrying wheels, framing, means suspending the framing on the axle, a pair of similar jointed rod devices connected at their forward ends to the framing by ball joint devices, arms fixed on the axle, resilient torque reaction connections between the rod devices and the arms allowing limited relative rotation thereof, and means restricting relative movement of the axle and framing in a direction transversely of the car.
